[57] **CLAIM**

The ornamental design for tool handle, as shown and described.

DESCRIPTION

FIG. 1 is a top plan view of my tool handle showing my new design.

FIG. 2 is a front elevation view, the backside being a mirror image thereof except for the protuberance thereof,

FIG. 3 is a side elevation view, the opposite side being a mirror image thereof,

FIG. 4 is a bottom plan view thereof.
